PHONOGRAPHIC DEVICE

Ladis H. Ottofy, Chicago, Ill.

Application December 30, 1939, Serial No. 311,711

4 Claims. (Cl. 274—11)

This invention relates in general to a manually operated sound producing device for reproducing various sounds such as words, music, phrases, and the like, and has more particular reference to the provision of an inexpensive, simplified structure which is economical to manufacture, easy to assemble and operate, and not likely to get out of order.

An important object of the invention is in the provision of improved means for guiding a sound record strip to insure the proper contact of the sound producing portion of the strip with an amplifier or diaphragm to which it is applied.

A further object of the invention is in the provision of a sound producing device consisting of a card or cardboard adapted to be held in one hand by engaging the edges of the card and a sound producing strip adapted to be inserted through the card and in contact therewith to be grasped by the other hand so that the maximum vibratory or sound producing effect will be obtained.

Other and further objects of the invention will appear hereinafter, the accompanying drawing illustrating the preferred structure and modifications thereof, in which

Fig. 1 is a face view of a phonographic device in accordance with this invention;

Fig. 2 is a side elevation partly in section showing a phonographic strip as applied to a card;

Fig. 3 is an enlarged view showing the engagement of the sound producing strip; and

Figs. 4, 5 and 6 illustrate modifications in which the sound producing strip is inserted through a diaphragm in contact with a sounding member and under a staple or through the diaphragm to insure contact with the sounding member.

In the operation of sound producing devices of the talking card type in which an advertisement, greeting or other subject matter is applied to a display card or cardboard in which the phonographic strip is movable, the contact of the sound producing side of the strip with the edge of the card causes it to wear away and unless the card is made of material substantially as stiff or rigid as the material of the strip itself, the sound produced will not be clear and distinct. It is furthermore desirable in order to produce a clear and distinct sound that the phonographic side of the strip shall be maintained in close contact and engagement with a sounding device of harder material at all times in producing the sound.

The present invention obtains the desirable results by producing a sound producing member in the form of a staple which is firmly affixed to

the card or sounding diaphragm in such relation to perforations through the card that when the sound producing strip is inserted through both perforations it will form a loop with the sound producing side confined in engagement with the sound producing member.

Referring now more particularly to the drawing, a display card or diaphragm 8, preferably a thin sheet consisting of several layers of cardboard or the like, is formed in a convenient size to be held in the hand. This card may be printed or decorated in any suitable manner, preferably as a birthday, Christmas, or a greeting card, or it may be for any other use such as an advertisement, and a message, word, or other sound relating to the printed matter on the card or independent thereof, may be provided on the phonographic strip 9 which preferably has one smooth side 10 and a phonographic side 11, although both sides of the strip may be provided with a phonographic message if desired.

In the card shown by Figs. 1 and 2, perforations 12 and 13 are spaced apart on the card and are of sufficient size so that the strip 9 may be inserted freely therethrough, preferably from the back through the upper opening, forming a loop on the face by inserting it through the lower opening. In order to distinguish the starting and finishing ends of the strip, the starting end 14 is sharpened and the finishing end 15 is rounded.

Ordinary cardboard will soon become worn by the engagement of the roughened side of the phonographic strip which usually is of harder material than that of the card and if thus rounded and worn it does not transmit the vibrations or sound from the strip with sufficient clearness.

A staple 16 is applied to the card at the edge of the opening 12, the ends of the staple being fastened through the card upon the rear or reverse side thereof in such a location that when the phonographic strip is inserted through the perforations of the card to form a loop at one side thereof the sound producing side of the strip will bear against the edge of the staple 16, thereby causing it to act as a bearing or sound producing member and communicating the vibrations imparted to it by the movement of the sound producing tape to the card itself. The card being held at its edges will vibrate at its central portion where the sound producing member is located and thus will produce the sound in accordance with the vibration produced by pulling the sound-producing strip through the card.

It is understood that the sound producing strip

may be of considerable length compared with the card so that when the pointed end 14 is inserted through the perforations 12 and 13 sufficiently to provide a hand grasping portion, the remainder of the strip which has not been pulled through the opening 12 will contain the message so that by pulling the strip in one direction the predetermined sound is produced by the diaphragm. To repeat the sound the tape may be pulled reversely through the card, giving off a jumbled or undistinguishable noise, and the strip may then be pulled through again in the proper direction, or the strip may be pulled entirely through the card from one end to the other and restrung through the openings as in the first place. It is necessary that the sound producing side of the tape be disposed against the sound producing staple 16 in order to produce the sounding vibration of the card.

In Fig. 4 a sounding staple 20 extends across a circular opening 21 for contact of the sounding strip therewith but instead of passing through another opening in the card, the strip is passed under a staple 22 which projects from the face of the card, the result being that the strip when pulled through the opening is held downwardly on its sound-producing side against the staple 20 by reason of its engagement under the other staple 22.

As shown in Fig. 5 the tape passes between two sounding staples 25 and 26 extending across an opening 27 or having an opening in the card between the staples through which the strip is inserted and the forward or advance end of the strip may be inserted through another opening 28 or under a staple 22 as shown in Fig. 4.

It is also contemplated that a fastening clip 30 having spring extremities 31 inside of a rectangular portion 32 having an end bar 33 may be applied over the edge of a card 34 so that the end bar 33 is located over an opening 35 through which a sound-producing strip may be inserted to engage the bar and then extending in a loop through an opening 36 or under a staple as shown in Fig. 4.

In all of these forms it will be apparent that a loop is produced at one side of the card which insures that the sound-producing side of the tape will be held in close contact or engagement with the sound-producing member or staple, thus causing the sound-producing vibrations to be imparted to the card so that the card will give off the maximum and most distinct reproduction of sound caused by the strip.

I claim:

1. In a phonographic device, a sheet sounding diaphragm having an opening therethrough at a distance from the edges, a vibration transmitt-

ing member extending across the opening and secured to the diaphragm, a sound record strip to extend through the opening having a record sound track at one side thereof engaging the member, and the diaphragm being formed with means at a distance from the opening for confining the intermediate portion of the strip in contact with the diaphragm and insuring that the sound track side of the strip is held in contact with the vibration transmitting member when the strip and diaphragm are relatively moved.

2. In a phonographic device, a sound record strip having a recorded sound track at one side thereof, a sheet sounding diaphragm provided and formed with an opening through which the strip is inserted, and with means spaced from the opening for confining an intermediate portion of the strip therebetween with the sound track facing the diaphragm centrally thereof, and a vibration transmitting member at the edge of the opening engaged by the sound track side of the strip when moved through the opening toward said means, and the opposite side of the strip being drawn against said means when the strip is moved in the intended sound producing direction.

3. In a phonographic device, a sound record strip having a recorded sound track at one side thereof, a sheet sounding diaphragm having an opening through which the strip is inserted and a vibration transmitting member at the edge of the opening, a staple extending from the diaphragm at a distance from the opening for confining an intermediate portion of the strip between the staple and the opening with the sound track engaging the vibration transmitting member at the edge of the opening when the strip is moved through the opening and under the staple, and the opposite side of the strip being drawn against the inner side of the staple when the strip is moved in the intended sound producing direction.

4. In a phonographic device, a sound record strip having a recorded sound track at one side thereof, a sheet sounding diaphragm formed with an opening through which the strip is inserted, a vibration transmitting member at the edge of the opening, another opening spaced from the first opening through which the strip is also inserted for confining an intermediate portion of the strip between the openings with the sound track engaging the vibration transmitting member to insure that the sound track side of the strip will engage the vibration transmitting member when it is drawn through the openings in the intended sound producing direction.
